Inventor
Charles F. Waite
By Jas. H. Churchill
Attest,

UNITED STATES PATENT OFFICE.

CHARLES F. WAITE, OF BOSTON, MASSACHUSETTS.

TOY OR GAME.

Application filed December 4, 1920. Serial No. 428,357.

To all whom it may concern:

Be it known that I, CHARLES F. WAITE, a citizen of the United States, residing in Boston, in the county of Suffolk and State 5 of Massachusetts, have invented an Improvement in Toys or Games, of which the following description, in connection with the accompanying drawings, is a specification, like characters on the drawings representing like parts.

This invention relates to a game or toy with which the game of base ball may be played in practically the same manner as the out door game is played.

15 To this end, the game or toy is provided with a base member having a regular diamond outlined thereon, and also having means whereby base hits, runs, outs and all the plays of the outdoor game may be 20 scored with the exception of the base on balls and stolen bases. The base member also has mounted on it a device representing a batter, which device is movable so as to enable it to strike the ball. The batter 25 is preferably mounted on a rotatable support or turn table which is capable of being turned so as to position the batter into different positions with relation to the diamond. The base member may and pref- 30 erably will be provided with representations of the nine players in the field.

These and other features of this invention will be pointed out in the claims at the end of this specification.

35 Fig. 1 is a plan view of a game or toy embodying this invention.

Fig. 2, an elevation of Fig. 1 looking toward the top of the sheet and broken away to disclose the batter and ball.

40 Fig. 3, a plan on an enlarged scale of the turn table and batter mounted thereon separated from the base member shown in Fig. 1.

Fig. 4, a section on the line 4—4 Fig. 3, 45 showing also the base member.

Fig. 5, a section on the line 5—5, Fig. 1.

Fig. 6, a section on the line 6—6, Fig. 3, with the base member added.

Referring to the drawing *a* represents the 50 base member which may be made of wood or other suitable material and on which is outlined the diamond *b*. The base member *a* is provided with upright walls *c* which represent the limits or fences of the grounds.

55 The base member *a* is provided with de- pressions or cavities at each corner of the

diamond *b*, and which represent home plate 10, first base 12, second base 13, and third base 14.

The base member *a* is also provided with 60 in the diamond with the depression or cavity 15 representing the pitcher and outside of the diamond with the depressions or cavities 16, 17, 18, 19, 20, which represent respectively the catcher, short stop, left, center and 65 right fielders. It is preferred to associate with the various depressions or cavities referred to, figures of the players assigned to the different positions represented by the depressions or cavities referred to, 70 which figures may be painted on or otherwise affixed to the base member *a*.

The base member *a* supports a device 21, which represents a batter, which device has 75 affixed to it a bat 22, which is designed to hit the ball 23 of suitable size to rest in the depressions or cavities. The device 21, which may be termed the batter, is represented as mounted on a pivot pin 24, which is preferably supported by a turn table or 80 rotatable support 25, which is mounted to turn in an opening in the base member *a* and is supported by the latter, see Figs. 3 and 4. The pivot pin 24 is extended through the turn table 25 and is provided with a 85 crank 26, which is connected by a spring 27 with a stationary pin 28 depending from an arm 29 secured as by screws 30 to the turn table 25. The crank 26 has connected with it a string 31 provided with a ball 32 constituting a handle.

The ball 32 is designed to be grasped by the child or other operator and drawn upon to turn the pivot pin 24 against the opposition of the spring 27, so as to move the batter 95 21 with relation to ball 23, and when the string 31 is released by the operator the spring 27 turns the batter in the opposite direction and causes the bat 22 to hit the ball 23 and knock it toward the players. 100

If the batted ball lands in the first base depression or cavity 12 a single hit has been made by the batter; if it lands in the second base depression 13 a double has been made; if it lands in the third base depression 14 a 105 triple has been made, and if it strikes the outfield fences or walls and lands in the home plate depression 10 a home run has been made.

If the batter makes a single hit by landing 110 the ball in the first base depression 12, a man is on first. If the batter on his next try

lands in the second base depression 13, the man on first is advanced to third base and two men are now on the bases, one on third base and another on second base. If the 5 batter on his next try knocks a single by landing the ball in first base depression 12, the players on second and third are advanced home and two runs are scored.

If the batter lands the ball in the depression 17 of the short stop or in that of any of 10 the outfielders, or of the pitcher or catcher, the batter is out.

If the ball does not land in a depression and stops rolling inside the foul lines 35, 36 15 of first and third bases, a strike has been made, and on three strikes the batter is out, and three outs retire the side. If the ball hit by the batter rolls outside the foul lines, the first two fouls are called strikes as in the 20 outdoor game as now played. After two fouls the batter must hit the ball until he either makes a hit or is out.

By mounting the batter on the movable support or turn table 25, the latter can be 25 turned so as to direct the batted ball in a given or desired direction and thereby effect what is called place hitting.

In Fig. 1, the turn table is shown by full 30 lines in its central or normal position and the batter is positioned to knock the ball toward second base. If it is desired to place the ball in the first base depression, the arm 29 is moved by the operator into its dotted line position marked 40 so as to position the batter toward first base. If it is desired to 35 place the ball in the third base depression, the arm 29 is moved into its dotted line position marked 41. It will be observed, that the ball can be batted with varying degrees 40 of force depending upon the amount of tension or force imparted to the spring 27 by pulling on the cord 31, which enables the batter to try for a single, two bagger, three bagger or home run.

If the player desires to try for a home run, the turn table is moved so as to position the batter toward the right field wall or fence, and the string 31 is pulled to impart 45 to the spring 27 its maximum tension or force, which is sufficient to cause the ball to 50 strike the right field fence, carom to the left field fence and return to the home plate depression, or the turn table can be turned into the position indicated by the dotted lines 41 55 and the play made from the left field fence.

It will be observed that with the toy or game herein shown, all the plays of the out-

door game of base ball may be made, except the base on balls and stolen bases.

While it is preferred to employ the turn 60 table, it is not desired to limit the invention in this respect. The base member *a* may be provided with suitable legs or posts 43.

One construction of game or toy embodying the invention is herein shown, but it is 65 not desired to limit the invention to the particular construction shown.

Claims:

1. In a game of the character described, in combination, a base member provided with 70 depressions or cavities arranged to represent a base ball diamond and the players' positions thereon, and having upright walls to limit the area of the ball ground, and 75 form the right, left and center fields thereof, a turn table mounted on said base member to turn freely thereon, a batter mounted on a pivot pin supported by said turn table to be moved therewith and to be rotated independently thereof, a bat carried by said batter, and means for turning the turntable to 80 position the batter toward the right or left fields, and means for turning the batter independently of the turntable.

2. In a game of the character described, in 85 combination, a base member, a turntable mounted on said base member to turn freely thereon, a batter pivotally mounted on said turntable to move therewith and to be turned thereon, a bat rigid with said batter 90 and extended downward to near the upper surface of the turntable to co-operate with a ball at rest on said turntable, and means for turning said batter to cause the bat to strike the ball on said turntable.

3. In a game of the character described, in combination, a base member provided with an opening extended through it, a turntable mounted in said opening to turn 95 freely therein, an arm attached to the under- 100 side of said turntable for turning the latter in said opening, a pivot pin extended through said turntable and rotatable therein, a batter mounted on said pivot pin above the turntable to turn with said pin, a bat carried by said batter and inclined downward to near the turntable, a spring to turn the pivot pin in one direction in said turntable to cause the bat to hit a ball at rest on the turntable, and means for turning the 105 pivot pin in opposition to said spring.

In testimony whereof, I have signed my name to this specification.

CHARLES F. WAITE.
